UNITED STATES PATENT OFFICE

2,217,800

PRINTING PRESS

Jacob A. Hollander, Chicago, Ill., assignor to
 Western Printing Machinery Company, Chicago, Ill., a corporation of Illinois

Application November 30, 1936, Serial No. 113,390

8 Claims. (Cl. 101—173)

This invention relates to multiple color printing presses and mainly to flat bed printing presses of the rotary impression cylinder kind, in which separate sheets of paper are fed and printed successively, and more especially to flat printing plate presses of the Miehle type, amplified and adapted for printing more than two colors.

Heretofore, presses of the flat bed sort have been used extensively for one-color and two-color work, in the latter case there being two impression cylinders arranged side by side, one for each color, and both operating on separate parts of a common reciprocating bed.

My present objects are mainly to increase the color range capacity of a Miehle style of press; to accomplish this with a minimum increase in cost for the machine and without increasing the ground size or plan area of the press; to provide for this and the use of rotary printing plates by mounting an additional cylinder directly over one or each of the original cylinders; and to provide for throwing the additional cylinder or cylinders into and out of printing service quickly and conveniently without affecting the other cylinders or their operation.

Further objects are:

To print three or four colors on a modified flat bed press originally intended for printing one or two colors.

To permit operation of the press substantially as originally constructed, whenever desired, in printing one or two colors.

To provide rotary printing cylinders cooperating with existing impression cylinders and flat printing bed, so as to effect the simultaneous printing from both flat and curved plates.

To provide primary control mechanism whereby the rotary printing cylinders are caused to follow the impression cylinders in their movements to establish printing and nonprinting relations with the printing bed.

To provide secondary control mechanism for the printing cylinders, whereby the latter are caused to establish printing or nonprinting relation with the impression cylinders, operating independently of, yet simultaneously with, the primary control mechanism.

To provide a disengaging mechanism or trip device associated with the secondary control mechanism whereby the printing cylinders are caused to be maintained in a nonprinting relation with the impression cylinders.

To provide an effective and efficient adjusting mechanism for the composition inking rollers so

as to control accurately the degree of contact with the ink drums.

To provide self aligning features for the composition inking rollers.

I will first explain generally the nature of my invention and how it relates to certain prior devices.

The form here shown comprises a self-contained third color printing unit built into or upon a two-color Miehle flat-bed printing press, as will be apparent.

This unit is so constructed that a heavy form may be printed on a full sized sheet with perfect registration without sacrificing speed of press or causing any disturbance to the original functions of the Miehle press. Also the press may be used for ordinary two-color work by merely sliding the cylinder gear out of mesh of the second impression cylinder gear.

The entire unit is bolted to the Miehle frame above the second impression cylinder and my plate cylinder bearing is securely bolted to the Miehle second impression cylinder bearing by long alloyed steel strain rods. This will permit the printing of a heavy form.

The plate cylinder is made to synchronize perfectly with the impression cylinder in all of its motions, yet no additional load is imposed on existing springs. Separate springs fitted in the main frame and functioning independently of the press mechanism operates the plate cylinder off the impression stroke. The tripping mechanism operates a heavy eccentric shaft which causes the impression, the controls of which are located at the feeder's position and are fully automatic, when operating as a three-color press. When operating as a two-color press, these controls are safely locked out of use.

The inking mechanism is carried in substantial frames forming part of the plate cylinder box. The form is quadruple rolled by two form rollers which assure adequate distribution. Each form roller is in contact with vibrator drums, which are in turn served by distributors in contact with a third vibrating drum of large capacity. An additional distributor makes contact between a large drum and stationary receiving drum, the latter being served directly from the fountain by the doctor roller.

The roller sockets are of a new quick acting type, mounted inside of the frame line to avoid the excessive springing. All rollers are designed with an independent adjustment for each contact. Therefore, one roller contact may be set without disturbing the adjustment of any other.

In the printing of three colors in one operation without the paper leaving the cylinder grippers, the register is positive and not affected by shrinkage or expansion of the paper. The plate cylinder is one-half the diameter of the impression cylinder and makes four revolutions to each impression, so there is perfect inking of the form.

The use of my third color unit requires no departure from the established operating routing. 10 An experienced Miehle pressman needs only to familiarize himself with the roller and impression adjustments, a matter of but a few minutes. It is to be understood, however, that the said unit actually applies the second color on three 15 color work, and what is normally the second color on the Miehle press becomes the third color in the present sequence.

The cylinder is equipped for the so-called Claybourn plate lockup as standard, but it is feasible 20 to furnish cylinders equipped for the so-called Blatchford lockup if such is preferred.

This improvement is desirable because of the economy in printing and absolute register. It enables work to be done at a substantially lower 25 price than could ordinarily be done on a two-color Miehle press.

The success of this unit has been assured by commercial reduction to practice in a large printing establishment.

30 This invention is illustrated by the accompanying drawings, in which:

Figure 1 is a fragmentary front side view of a printing press of the so-called Miehle type having the present improvement and shows the structural features of the present invention in end elevation in full lines, with the plate-cylinder control trip and latch set for printing, the adjacent parts of the old Miehle press being shown in dotted lines, with remote parts broken away.

40 Fig. 2 is a sectional view on the line 2—2 of Fig. 3.

Fig. 3 is an irregular cross sectional view on the line 3—3 of Fig. 2.

45 Fig. 4 is an enlarged detail view of the tripping mechanism for the plate cylinder in its disengaged and nonprinting position, one extreme outward position of the cam roller lever being shown in dotted lines, and its opposite position being shown in full lines.

50 Fig. 5 is a fragmentary detail sectional view similar to Fig. 2 but with the plate cylinder raised to its nonprinting position.

55 Fig. 6 is a diagram showing the relation of the two impression cylinders and the associated cylinders, with arrows indicating the direction of movement of sheets of paper through the press, the present plate cylinder being shown in full lines at the left and a possible future plate cylinder being indicated by dotted lines at the right.

60 A brief general description of a two-color Miehle press will aid in understanding the application of this invention to such a press. Briefly a two-color Miehle press consists of a suitable frame on which a bed having two flat-plate printing sections is made to travel in printing contact with a pair of impression cylinders, which latter have a transfer cylinder interposed between them. Facing the feeder side, as in Figs. 1 and 6 there is a feed board on the right hand end of the machine, 70 and a delivery and stacking mechanism on the left hand end. The impression cylinders each have grippers which engage and carry the sheet. The transfer cylinder is equipped in like manner. The impression cylinders make two revolutions 75 to one complete forward and return cycle of the

bed. In operation, the first impression cylinder receives the sheet, carrying the same into contact with one of the bed printing sections. Approximately 1 1/4 revolutions later the sheet is taken by the transfer cylinder and transferred to the second impression cylinder which carries the sheet into printing contact with the other of the printing sections. Approximately 1 1/2 of a revolution later the printed sheet is delivered and stacked.

A tripping mechanism, not here shown, brings each of said impression cylinders alternately into printing contact with their respective printing sections of the bed. This mechanism, well known to those skilled in the art, is so devised as to bring the first cylinder down when the bed is traveling 10 towards the right end of the machine, and to raise the cylinder when the bed is traveling towards the left end of the machine. The second cylinder is 15 similarly controlled with respect to the left hand printing section.

20 The present invention concerns the mounting of rotary printing cylinders, one or more, above said impression cylinders, combined with novel mechanisms for bringing the printing cylinders into printing contact in proper sequence with the 25 operating sequence of the existing press. This is accomplished by removing the impression caps from the existing frame and using the surfaces thus exposed as foundations for mounting independently operating, yet synchronized units, to 30 which this invention is mainly directed.

The following description applies to each of these new units, only one of which is actually shown in full. These two added printing devices are substantially alike in their construction and 35 operation. Either one or both may be used.

I will first describe the parts of the existing press which are intimately associated with this invention. Thus, for instance, member 19 is the 40 press bed and member 20 is one of the impression cylinders previously mentioned, journaled in bearings 21 in boxes 22 vertically slidable in press frames 23. Return springs 25 backed in sockets (not shown) of the press frame are received about 45 cap rods 26 which latter secure the upper and lower halves of the boxes 22 together. The said cylinder 20 is driven by gear 24, (see Fig. 3), which meshes with the drive gearing of the press. An impression control mechanism indicated generally at 30 is provided for the purpose of bringing 50 the cylinder 20 into printing and nonprinting relation with the press bed.

This mechanism consists of an eccentric 31 co-operating with a shoe 32 slidable on the top surface of box 22. The concentric portion of the eccentric 31 is backed by the bearing block 33, which in turn is adjustable for various degrees of impression by impression screws 34, which are threaded into supplementary side frames 35. The impression screws 34 are operated by means of 60 adjusting worms 36, meshed with worm wheel portions 37 integrally formed with the impression screws. The eccentrics 31 are operated by levers 38 attached thereto, and pull rods 39 articulated with the timed tripping mechanism of the press, 65 which being well known is not here shown in detail.

The transfer cylinder 40 is carried on journals in bearings mounted on the side frames 23, as will be understood.

70 The following detail description relates more specifically to the subject matter of this invention. Thus, a printing plate cylinder 50 is fixed to shaft 51 having journals 52 carried in vertically slidable box frames 53 held in spaced relation- 75

ship by transverse members 53—A and 53—B. (See Fig. 3.) These box frames together with the members 53—A and 53—B form a complete housing in which the major portion of my invention operates.

The said supplementary side frames 35 are secured to the press frame 23 by cap rods 54. The housing 53, 53—A etc., is resiliently supported by springs 55 backed in sockets 57 of the 10 box frames 53.

Impression rods 58 are secured to the journal boxes 22, as for instance by being threaded to the cap rods 26. The upper ends of said impression rods 58 are received through yokes 59. The 15 position of the yokes as related to the rods is adjustable by nuts 60 threaded to upper portion of the rods.

In order that printing pressure may be applied between plate cylinder 50 and impression cylinder 20 a cross shaft 61 is provided with eccentrics 62 cooperating with impression shoes 63 received under the yokes 59.

It will be noted that the mechanism thus far described relates to a means for causing the 25 plate cylinder 50 to follow the impression cylinder 20 in its movements, being integrally tied thereto by the impression rods 58. It will be further noted that through the eccentrics 62 on cross shaft 61 and its related shoes 63 and yokes 30 59 the degree of contact pressure of plate cylinder 50 on impression cylinder 20 can be accurately controlled by means of the adjustment nuts 60.

The plate cylinder 50 is driven by means of 35 gear 70 mounted freely on the shaft 51 and meshing with gear 24 of the impression cylinder 20. For the purpose of shifting to a limited extent the surface relation between the plate cylinder 50 and impression cylinder 20, said gear 70 is 40 provided with a slot into which a drive dog 71, secured to a driver 72 keyed to the plate cylinder shaft 51, is received. The drive dog 71 is provided with adjusting screws 73 in order that the lateral position of the dog may be altered in the 45 slot.

It is possible to disconnect the driving means for the unit from the press entirely, as for instance, by providing the driver 72 with studs 75 to which sleeve nuts 76 are threaded. One of 50 the sleeve nuts is provided with a collar 77 which performs the function of pulling gear 70 out of mesh entirely with gear 24 and thereby locked against a barring hub 78 secured on shaft 51. By this means the unit can be entirely disengaged 55 from the press.

In order to bring the plate cylinder 50 into the proper printing and non-printing sequence, during operation of the press, a means is provided to oscillate the eccentric shaft 61. Thus a crank- 60 arm 80 is fixed to one end thereof and connected by link 81 to the free end of a rocking lever 82 journaled at its other end on shaft 83. A latch 84 is pivoted at 85 to lever 82. Said latch 84 has a pawl end 86 receivable in a notch 87 in a 65 cam roller lever 88 journaled on said shaft 83. A cam roller 90 rotatably mounted on said lever 88 is received in a cam slot 91 of a cam gear 92 freely rotatable on the cylinder shaft 51. Said cam gear 92 meshes with a compound gear 93 70 which in turn meshes with a stub gear 94 driven from a pinion 95 keyed to said cylinder shaft 51.

A housing or bearing 96 to which the front ends of shafts 61 and 51 are journaled forms a bearing support for gear 94. It will be noted that 75 rotation of the cam gear 92 will impart a rocking

motion to the lever 82 which in turn operates shaft 61 thereby forcing cylinder 50, together with the housing in which it is journaled, alternately towards and from the impression cylinder 20 accordingly as the various portions of the 5 cam 92 and slot 91 are presented to the roller 90.

A mechanism known generally as the "distribution" is provided for inking the plates on the plate cylinder 50. Thus, as shown in Fig. 2, form rollers 100 make contact with the plates or 10 cylinder 50 and also with vibrating drums 101 which in turn contact distributing rolls 102 in contact with intermediate vibrator drum 103. An ink fountain 105 having fountain roller 106 is mounted on vertical support brackets 107. A 15 ductor roll 108, carried on arms 109 secured to a rock shaft 110 carries the ink from said roller 106 to a receiving drum 111, which makes a distributing contact through the distributing roll 112 with the intermediate vibrating drum 103. 20

The vibrating drums 101 and receiving drums 103 and 111 are driven from the plate cylinder 50, by an idler gear 115 which meshes with the gear 72—70 and also with gears 116 keyed on the shafts of vibrating drums 101. Said gear 115 25 also meshes with a gear 117 fixed to the shaft 103 of said drum 103. The gear 118 keyed to the shaft of receiving drum 111, is driven by means of a gear 119 meshing with the gear 117.

The gears 116 and 117 are wide faced gears to 30 enable the drums 101 and 103 to have an endwise or vibrating motion and at the same time have imparted to them a rotary motion. It is the usual procedure to provide one or two back and forth motions of the drums to each printing cycle, 35 therefore the gear 119 is keyed to a drive shaft 120 which forms the drive connection to a gear box indicated generally at 121. A worm 122, keyed on the shaft 120, meshes with worm wheel 123 on shaft 124 journaled in the gear box. An 40 eccentric 125 is mounted on the exposed end of the shaft 124 and is received within the eccentric strap 126 connected to a rock shaft 127 by means of a connecting rod 128, mechanically connected to an arm 129 of a bell crank 130 secured to the 45 rock shaft 127. The rock shaft 127 has also mounted thereon a rocker arm 131 on the outer ends of which are rollers 132 received in spools 133 secured to the exposed ends of said vibrating drums 101. The bell crank 130 is similarly 50 equipped with rollers 132. Rock shaft 127 is carried in a bearing 134 secured to the housing.

The mechanism described imparts vibratory motion to the drums in such a manner as to cause drum 103 to travel backward while drums 101 55 travel forward and vice versa.

It is the usual procedure to rotate but partly the fountain roller while the ductor roller 108 is in contact therewith. Thus bell crank 140 is journaled on the outer end of the fountain roll 60 shaft 106'. A ratchet 141 is keyed to this shaft and co-acts with a pawl 142 urged towards the ratchet by spring 143 mounted on the bell crank 140. A rocking motion is imparted to the bell crank 140 by means of connecting rod 143, one 65 end of which is pivoted to the crank plate 144 secured to a shaft 145. This shaft has a worm wheel 146 secured thereto which meshes with a worm 147 fixed on the shaft 124.

The ductor roll 108 is operated by means of a 70 cam 150 secured to the exposed end of shaft 145 and co-acts with roller 151 on arm 152 secured to the rock shaft 110. The ductor roll is forced against the fountain roll 106 by the cam during its forward motion and is returned by return 75

springs 153 received about plungers 154, the upper ends of which are pivoted to arms 155 fixed on the rocker shaft 119. The lower end of the springs is backed against swivel stop 155 mounted in the vertical frame supports 107, which also serve as guides for said plungers 154. A regular press operated device actuates the said means 82, etc., whereby the printing cylinder 50 may be maintained in non-printing relation with reference to the impression cylinder 20. Thus the latch 84 may have its pawl end 86 disengaged from the notch 87 by means of a segment 169 forming a portion of the rocker lever 161 (see Fig. 1). Latch 84 is provided with a roller 162 which rides upon said segment 169 when the latter is brought within range of the said roller, while the cam lever assembly 88 is moving outward, thereby disengaging the lever 82 entirely from the cam lever 86. Thus the cam lever 88 is released and will operate idly without affecting any motion of the eccentric shaft 61.

In order to cut in or out the operation of the rocking lever 82 with its segment 169, the upper end of a connecting rod 164 is pivoted thereto at 165. The lower end is subject to manual control, subject to appropriate timing safeguards as may be inferred though they are not a part of the present invention.

30 In order to prevent feeding of ink while the plate cylinder is in non-print relation and thereby prevent loading of the printing plates with too much ink, means are provided to prevent motion of the fountain roll. A connecting rod 35 208 is attached to the lever 161 at 201, and at 202 to a rockable cam 203, which has a high portion 204 adapted to hold the pawl 142 out of possible engagement with the ratchet 141 thus preventing the fountain from functioning.

40 Operation

Considering first the simpler embodiment of my invention, adapted for three-color work, as illustrated by Fig. 2, the paper stock in the form of rectangular sheets of paper 1 are fed in over a feed board or guide 2 to the primary impression roll or cylinder 20'. This picks up the sheets one at a time and carries them around to the flat printing plate 3 on the bed 19. Thence, each sheet is carried by cylinder 20' to the transfer cylinder 40 and thence by the secondary cylinder 20 to the plate cylinder 50, and then down to the other flat plate 4, from whence it is carried by cylinder 20 to the discharge or delivery means 5.

On Fig. 6 the number of color impressions supposed to be on a sheet at a given time and place is indicated by the number of little circles. (Cylinder 50' not being in use.)

Assuming now a four color press, the sheet goes first to cylinder 20' which carries it at once 60 operatively under the printing cylinder 50'. (See Figs. 2 and 6) Thence it goes by cylinder 20' to plate 3 and thence in order by cylinder 20' to transfer cylinder 40, to cylinder 20, operatively under cylinder 50, by cylinder 20 to plate 4 and by cylinder 20 to delivery 5.

It is to be understood that some of the details set forth may be altered or omitted without departing from the spirit of the invention as defined by the following claims.

70 I claim:

1. A tricolor printing press comprising two parallel impression cylinders and a printing cylinder in triangular arrangement, a two section printing plate for said two cylinders, means to feed successive sheets of paper to said cylinders in pro-

gressive order through the press, and means to ink the several plates and printing cylinder appropriately according to a chosen color scheme.

2. In a printing press, a flat printing bed, means for imparting reciprocating motion to said bed, a primary impression cylinder, a secondary impression cylinder, a transfer cylinder interposed between said primary and said secondary impression cylinders, a printing cylinder for each of said impression cylinders, means for imparting continuous rotary motion to all of said cylinders at the surface speed of said bed, and means for establishing printing and non-printing relations between said impression cylinders and said bed, and said impression cylinders and said printing cylinders.

3. In a printing press a bed having two flat printing sections, means for imparting reciprocating motion to said bed, a primary impression cylinder devised to co-operate with one of the sections of said bed, a secondary impression cylinder devised to cooperate with the other of the sections of said bed, a transfer cylinder interposed between the said impression cylinders, printing cylinders one for each of said impression cylinders, means for imparting continuous rotary motion to all of said cylinders at the surface speed of said bed, means for establishing printing and non-printing relation between said impression cylinders and said bed, and between said impression cylinders and said printing cylinders, and means whereby non-printing relation may be selectively maintained between said impression cylinders and one or both of said flat printing sections and one or both of said printing cylinders.

4. A Miehle printing press of the two impression cylinder flat pressbed type in combination with a printing cylinder mounted adjustably on the lift frame support of one of the impression cylinders and means on said lift frame to throw the said printing cylinder into and out of printing relation to the corresponding impression cylinder.

5. A flat bed Miehle printing press and attachment therefor comprising a printing plate cylinder having a journal support which is liftably mounted on the journal support frame of one of the impression cylinders of said press, and means to lift and depress said journal support comprising spring and cam means respectively carried by said journal support frame, and control linkage means connected and operatively related to synchronize said cam means with corresponding rotary positions of the said plate and impression cylinders.

6. A flat bed Miehle printing press and attachment therefor comprising a printing plate cylinder having a journal support which is liftably mounted on the journal support frame of one of the impression cylinders of said press, and means to lift and depress said journal support comprising spring and cam means respectively carried by said journal support frame, and control linkage means to mutually integrate the operation of said cam, plate cylinder and impression cylinder together with manual control means to throw out of gear and operation said cam and plate cylinder.

7. A printing press comprising in combination a frame, a reciprocating plate-bed thereon, an impression cylinder thereabove, a vertically movable support for said cylinder adapted to adjustably shift up-and-down in its relation to said bed, a rotary printing-plate cylinder above said

support, a support for said plate cylinder mounted rigidly on the first said support and adapted to change up-and-down the relation of said plate cylinder to said impression cylinder, said frame

5 having a fixed track to guide said plate-bed.

8. In a printing press, a reciprocating plate-bed, a rotary plate cylinder and an impression cylinder interposed, in combination with means to feed paper in printing relation thereto, means

10 to raise and lower said cylinders as a unit rela-

tive to said plate-bed for flat-plate printing, means to raise and lower said plate cylinder relative to said impression cylinder for curved plate printing, and timing means set to occlude said cylinders for printing thereby during their joint downward movement and for separating them during the flat plate printing periods and during up-movement of said cylinders.

5

JACOB A. HOLLANDER. 10
